Primary Examiner — Cathron C Brooks*Assistant Examiner* — Sharon S Oum(74) *Attorney, Agent, or Firm* — John G. Powell; S. Robert Chuey(57) **CLAIM**

The ornamental design for a jar, as shown and described.

DESCRIPTION

FIG. 1 is a perspective view of a jar, showing our new design;

FIG. 2 is a front side view of the jar of FIG. 1;

FIG. 3 is a first side view of the jar of FIG. 1;

FIG. 4 is a back side view of the jar of FIG. 1;

FIG. 5 is a second side view of the jar of FIG. 1;

FIG. 6 is a top view of the jar of FIG. 1;

FIG. 7 is a bottom view of the jar of FIG. 1;

FIG. 8 is a perspective view of another embodiment of a jar, showing our new design;

FIG. 9 is a front side view of the jar of FIG. 8;

FIG. 10 is a first side view of the jar of FIG. 8;

FIG. 11 is a back side view of the jar of FIG. 8;

FIG. 12 is a second side view of the jar of FIG. 8;

FIG. 13 is a top view of the jar of FIG. 8; and,

FIG. 14 is a bottom view of the jar of FIG. 8.

The broken lines shown in the drawings illustrate portions of the jar that form no part of the claimed design.

1 Claim, 8 Drawing Sheets(56)
